UNITED STATES PATENT OFFICE

136,502

DESIGN FOR A COMBINED TOOL HOLDER AND CUTTING DEVICE FOR LATHES

Arpad J. Havas, Jackson Heights, N. Y.

Application July 23, 1943, Serial No. 110,738

Term of patent 7 years

To all whom it may concern:

Be it known that I, Arpad J. Havas, a citizen of the United States, residing at Jackson Heights, in the county of Queens, and State of New York, have invented a new, original, and ornamental Design for a Combined Tool Holder and Cutting Device for Lathes, of which the following is a specification, reference being made to the accompanying drawing, forming a part thereof, in which

Fig. 1 is a top plan view of a combined tool holder and cutting device for lathes embodying my new design.

Fig. 2 is a side elevational view of Fig. 1.

Fig. 3 is a bottom plan view of Figures 1 and 2, and

Fig. 4 is an end elevational view of Fig. 1.

The dominant features of the design reside in the portions shown in full lines.

I claim:

The ornamental design for a combined tool holder and cutting device for lathes, as shown and described.

ARPAD J. HAVAS.
